OIL CLEANER AND TEMPERATURE
REGULATOR

John G. MacCormack, New York, N. Y., assignor
to Transportation Appliances, Inc., New York,
N. Y., a corporation of New York

Application December 17, 1937, Serial No. 180,283

4 Claims. (Cl. 210—122.5)

This invention relates generally to means for cleansing and controlling circulating lubricating oil used in internal combustion engines.

It is generally recognized that the temperature of lubricating oil circulated from the sump or crank case of a gasoline or fuel oil internal combustion engine becomes at times so high as to break down the physical structure of the oil. At other times, as at periods of engine starting or under low atmospheric temperature, the chilled oil does not flow properly until after a considerable period of initial engine operation. From engineering tests it has been ascertained that power loss and cylinder wear is greatest when engine temperatures are below 140 degrees F., while, on the other hand, when engine temperatures are above 170 degrees F., lubricating oil temperature is correspondingly raised to the point tending to cause reduction of the viscosity of the oil to an extent likely to impair its lubricating efficiency, with consequent risk of undue cylinder wear from this cause.

Having these circumstances in view, it is an object of this invention to provide a novel, simple and efficient apparatus operative to control engine lubricating oil temperature so as to maintain the same within desired limits calculated to prolong its efficient use life.

I have also found that to maintain engine lubricating oil within safe temperature limits, it is highly desirable to remove contaminating substances therefrom, such as sludge, carbon, road dust, etc., it being known that transfer of heat to or from contaminated oil, heavy with insolubles, is exceedingly difficult. This invention, therefore, has for a further object to provide, in my novel oil temperature regulating apparatus, means for cleansing the oil by removing therefrom accumulating impurities.

I have also observed that sludge formed in engine lubricating oil contains a considerable percentage, rarely less than 12 per cent, of oxidized binders which form hard asphaltic or paraffinic deposits in filters, and which tend to impede both free flow of oil in the oil circulating system of an engine, as well as to impede dissipation of heat from the oil thus permitting the rise of abnormal engine operating temperatures. This invention, therefore, has for another object to provide an oil filtering or cleansing medium which is impregnated with a solvent adapted to dissolve the gum residue released by oxidation of the oil in the engine, whereby the accumulation of sludge in the filtering medium takes place more slowly, with the consequence that the efficient operative life

of said medium is prolonged, while at the same time giving back to the lubricating oil constituents lost through excess engine heat, so that the oil is maintained in free flowing condition for longer periods of useful life, and tendency to formation of gum deposits in the engine and oil circulatory system is greatly reduced.

Other objects of this invention, not at this time more particularly enumerated, will become apparent from the following detailed description of the same.

An illustrative embodiment of this invention is shown in the accompanying drawings, in which:

Fig. 1 is a front elevation of the novel oil cleaner and temperature regulator device according to this invention; Fig. 2 is a side elevation of the same; Fig. 3 is a longitudinal vertical section through the same, taken on line 3—3 in Fig. 1; Fig. 4 is a top end view of the same; and Fig. 5 is a horizontal sectional view, taken on line 5—5 in Fig. 3.

Similar characters of reference are employed in the above described views, to indicate corresponding parts.

Referring to the drawings, the reference character 10 indicates the external casing of the device. This casing preferably consists of a tubular metallic shell having open bottom and top ends. Suitably affixed to and surrounding the major portion of said casing, intermediate its ends, is an enveloping jacket shell 11 forming between the same and the casing an annular chamber 12 through which is circulated a heating fluid. Connected to an inlet 13, adjacent to the lower end of said jacket shell 11, is a heating fluid supply conduit 14, and connected to an outlet 15, adjacent to the upper end of said jacket shell 11, is a heating fluid return conduit 16. A heating fluid, such as exhaust gas from the engine served by the device or hot water from the engine cooling system, is caused to flow or circulate through the jacket chamber 12 in contact with the casing shell 10. The flow of the heating fluid may be controlled by means of any suitable type of thermostatically actuated control valve means (not shown), so that the heat applied to the casing shell may be maintained at a selected desired temperature degree. For example, the thermostatically actuated control valve may be set to close at 160 degrees F. and to open on a temperature drop below that point, thus maintaining a degree of heat as applied to the oil cleaner and temperature regulator device at approximately 160 degrees F. If, under such conditions, the engine lubricating oil flowing through

the internal structure of the device, enters the latter say at 130 degrees F., its temperature will be raised, by transfer of heat thereto from the heating fluid circulating through the jacket 5 chamber 12, to approximately 145 to 150 degrees F., which is a satisfactory oil heat. It will be understood that the applied heating fluid temperature will be set and controlled variably as given conditions may require, the above example 10 being mentioned only by way of illustration.

The open bottom end of said casing shell 10 is closed by a removable bottom head 17, the same having a skirting rim 18 to fit externally over and around the bottom end of said casing shell 10. A joint sealing gasket 19 is interposed 15 between the casing shell margin and the inner side of said bottom head.

In like manner, the open top end of said casing shell 10 is closed by a removable top head 20, 20 the same having a skirting rim 21 to fit externally over and around the top end of said casing shell 10. A joint sealing gasket 22 is interposed between the casing shell margin and the inner side of said top head.

25 Said bottom and top heads are respectively provided with means for securing the same tightly engaged in assembled relation to the casing shell. Each said means includes a bridging clamp bar 23, having a central internally screw threaded hub 24 through which is threaded a clamp screw 25. Said clamp bar is provided with hook-like extremities 26 to engage through perforate ears 27, which are affixed to and project upwardly respectively from diametrically 30 opposite sides of the casing shell 10. The head is provided with a centrally disposed upwardly open socket boss 25' to receive engagement of the free end of said clamp screw 25, which, when turned home, forces the hook-like extremities 35 26 of the clamp bar 23 against the upper ends of the slotted ears 27, thus giving purchase to the clamp screw 25 whereby it thrusts downwardly upon the head to firmly and tightly seat and seal the same to the end of the casing shell.

40 The bottom head 17 is cored to provide an oil inlet passage 28, to which may be suitably coupled a conduit (not shown) leading from the sump or crankcase of the engine, the line of said conduit including a suitable oil circulating pump (not shown). Mounted in connection with said bottom head 17, to open outwardly from said oil inlet passage 28, is a pressure reducing valve fitting 29, the port 30 of which is normally closed by a spring controlled valve member 31. 45 The outlet end of said valve fitting 29 is connected by a conduit (not shown) leading back to the sump or crankcase of the engine. If desired, said bottom head may be also provided with a drain port 32 which leads outwardly from 50 the bottom interior of the casing shell 10, said drain port being normally closed by a removable closure plug 33.

55 The top head 20 is cored to provide an oil outlet passage 34, to which may be suitably coupled a conduit (not shown) to deliver oil back to the sump or crankcase of the machine, or to any suitable lubricating oil distributing system with which the engine may be provided. Mounted in connection with said top head 20, to open into 60 the oil outlet passage 34 from the interior of said casing shell 10, is a pressure relief valve fitting 35, the port 36 of which is normally closed by a spring controlled valve member 37. The top head 20 is provided on its inner side with an internal boss or neck 38 formed to provide an in-

ternally threaded socket 39, with the interior of which the inner end of said oil outlet passage 34 communicates.

Arranged within the interior of said casing shell 10 is a means for cleansing and treating 5 the lubricating oil which is caused to flow through the interior of the device. The cleansing and treating means broadly considered comprises a cylindrical hollow container 40, preferably made of thin sheet metal. The diameter of said container is somewhat less than the internal diameter of the casing shell 10, so that when the same is fixed in place within the interior of the latter, a comparatively narrow annular intermediate space 41 is formed contiguous to the 15 casing shell wall, so that a relatively thin body of oil filling the same makes contact with the casing shell wall so that heat may be transferred to or from said oil body as, under varying circumstances, may be required. The container 20 40 is provided with a top end wall 42 having a centrally disposed discharge opening 43 bounded by an axially extending externally threaded throat 44; the latter screws into the threaded socket 39 of the neck 38 of said top head 20, 25 whereby the interior of said container is coupled in communication with the oil outlet passage 34 of said top head 20. The container 40 is further provided with a bottom end wall 45. The outlying portion of the interior of the container 30 40 is provided with capillary body or wicking 46, of substantial thickness, which extends upwardly from the bottom end wall 45 contiguous to the inner wall surface of said container. Provided in the bottom end wall 45 of the container are a 35 plurality of intake openings 47 which register with the bottom end of said capillary body or wicking 46 so as to give oil access thereto. Packed into the interior of said container 40 and in contact with the inner side of the capillary body or 40 wicking 46 is a mass of filtering material 48. This filtering material may consist of a suitable substance through which the oil may percolate, but preferably consists of a fibrous material such as cotton waste, cellulose or the like. Embedded 45 within the mass of filtering material 47, preferably in horizontally and vertically spaced apart relation so as to occupy respectively different positions within the mass of said filtering material, are interstitial bodies 49 adapted to provide by-pass oil flow paths in the filtering material mass. Illustrative of one means for producing said by-pass forming bodies, the same are formed by rolling woven wire mesh into cylindrical form, thus providing a more or less open or comparatively unrestricted passage space for oil flow at the points within the filtering material mass where these wire mesh cylindrical formations are embedded. The mass of filtering material is impregnated with a solvent combination of petroleum elements which will act with solvent effect upon gum residues, tars and other petroleum binders carried by the lubricating oil delivered thereto, thus maintaining for a longer time the normal physical structure 60 and free flowing condition of the lubricant.

65 It will be understood that although the above described oil cleansing and treating means may be made in a single unitary form, it is preferable, however, to furnish the same in a sectional unitary form as shown in Fig. 3, in which case a plurality of sections or units, each comprising the combination of elements above described, is employed, as, for example, the units A and B shown in Fig. 3. These units are connected to- 70 75

gether, but in such manner as to function individually, i. e., independently of each other. To effect this arrangement the upper unit A is provided at its bottom end with an internally threaded neck 50 to receive the externally threaded throat 44 of the lower unit B. The upper unit A is additionally provided with an axially disposed by-pass conduit 51 opening through its bottom end wall 45 so as to communicate with the discharge opening 43 of the lower unit B; the upper end of said by-pass conduit 51 communicates directly with the outlet passage 34 of the top head 20.

If desired the cleansing and treating means structure may be additionally supported and braced in its operative assembled relation by interposing between the bottom end of the same and the bottom head 17 a resilient supporting or bracing bridge spring 52.

The process of oil heat regulation with cleansing and revivifying effect, as carried on by and within the device above described, comprises the circulatory movement of oil from the engine crankcase through the device and back to the crankcase. When the engine is started the heat generated by the consumed fuel is transferred to the engine cooling jacket water which is also circulated through the chamber 12 of the jacket shell 11 so as to apply heat to the walls of the casing 10, or, if desired, exhaust gases of the consumed engine fuel may be utilized for like purpose.

It is desirable to maintain a flow of oil at a constant pressure through the device regardless of engine speed, so that sufficient time is allowed for both heat exchange and cleansing effects. Assuming, therefore, that the oil is delivered, by a suitable pumping means, from the engine crankcase, at comparatively high pressures, more or less variable proportionally to engine speed but, e. g., averaging about eighty pounds to the square inch, the oil enters and fills the interior of the device, but, by reason of the operation of the pressure controlling and regulating means with which the device is provided, is maintained, e. g., at a pressure within the device of approximately fifty pounds to the square inch. The oil at the comparatively high pressure reaches and enters the device through the inlet passage 28, but since this passage is provided with a pressure relief valve means 29-30-31 which is set to relieve pressures in excess, e. g., of fifty pounds to the square inch, said relief valve means will by-pass oil in excess of the latter pressure back to the engine crankcase, and consequently the oil pressure within the device is kept constant at the desired pressure of fifty pounds. This result is further assured by the provision of the additional pressure relief valve means 35-36-37 of the oil outlet passage 34 of the device, which operates, if internal pressure of oil within the device tends to build up beyond the desired fifty pounds, to relieve such excess pressure by direct discharge of the oil from the interior of the casing 10, which thus by-passes the cleansing and treating means.

Under the desired constant internal pressure the oil delivered into and filling the interior of the device is caused to fill the space 41 intermediate the walls of the casing 10 and the cleansing and treating means, and in contact with said walls so as to exchange heat. If the oil is at a temperature below 140 degrees F., the temperature of the casing walls being heated to say about 160 degrees F. by the thermostatically controlled circulation heating fluid through the

jacket chamber 12, heat will be transferred to the oil within the device to raise its temperature above the desired minimum of 140 degrees F. If, on the other hand, the oil is at a temperature in excess of 170 degrees F., heat will be transferred from the oil within the device to lower its temperature below the desired maximum of 170 degrees F.

The oil filling the interior of the device, and under the controlled pressure, passes inwardly 10 through the openings 47 in the bottoms of the cleansing and treating units and into contact with the capillary bodies or wickings 46. Said capillary bodies or wickings 46, by their capillary action quickly carry up the oil along the interior 15 sides of the said units so as to pass the same into the filtering material 48 through which the oil percolates. As the oil thus percolates through the filtering material, any impurities, sludge, gums, contaminating carbon, road dust, etc., is separated therefrom. At the same time, due to the presence of the solvent agent with which the impregnating material is impregnated, the accumulating gums and like elements tend to be dissolved and returned to the oil content so as to revivify 25 the same, leaving only the insolubles separated and held in restraint by the filtering material.

The oil as it leaves the device through the oil outlet 34 thereof returns to the crankcase at an efficient temperature and well cleansed of impurities, so that the entire content of lubricating oil with which the engine is supplied is kept for a maximum length of time in efficient serviceable condition.

Since the mass of filtering material is provided, 35 at different points within its mass, with the more or less open interstitial bodies 49, a by-pass path to different areas of the filtering material is assured, so that as said filtering material becomes choked with separated impurities and insolvents 40 easy passage may be provided for the incoming oil past the heavier deposit to cleaner areas of the filtering material, until the accumulations within the latter collect to such an extent that replacement of the cleaning and treating units is 45 advisable.

It will be understood that various changes may be made in the above described constructions, and many apparently widely different embodiments of this invention may be made without departing from the scope thereof as defined by the following claims. It is therefore intended that all matter contained in the above description or shown in the accompanying drawings shall be interpreted as illustrative and not in a limiting 55 sense.

I claim:

1. A device of the kind described comprising, a casing, means to apply a heat exchange fluid in contact with said casing, means for admitting oil to be treated into one end of said casing, means to discharge said oil at the other end of said casing, means to maintain the oil within said casing at a substantially constant pressure comprising an excess pressure relief valve cooperative with 60 the oil admission means and an internal pressure relief valve cooperative with the oil discharge means, and an oil cleansing means including a container within said casing spaced from the side walls thereof to provide a comparatively narrow 65 intermediate oil receiving space to dispose incoming oil in contact with the heated casing walls, said space being directly communicative with said internal pressure relief valve, a capillary means lining the side walls of said container, said con- 70 75

- tainer having oil admission means communicating with the lower end portion of said capillary means, a mass of filtering material filling said container and disposed contiguous to said capillary lining means, and said container having at its central top portions an oil outlet means connected in communication with the oil discharge means of said casing.
2. A device of the kind described as defined in claim 1, wherein said filtering material of the oil cleansing means is impregnated with a solvent adapted to dissolve accumulating gums, tars and the like carried in the oil under treatment.
3. A device of the kind described comprising, a casing, means to apply a heat exchange fluid in contact with said casing, means for admitting oil to be treated into one end of said casing, means to discharge said oil at the other end of said casing, means to maintain the oil within said casing at a substantially constant pressure comprising an excess pressure relief valve cooperative with the oil admission means and an internal pressure relief valve cooperative with the oil discharge means, and an oil cleansing means including a container within said casing spaced from the side walls
- thereof to provide a comparatively narrow intermediate oil receiving space to dispose incoming oil in contact with the heated casing walls, said space being directly communicative with said internal pressure relief valve, a capillary means lining the side walls of said container, said container having oil admission means communicating with the lower end portion of said capillary means, a mass of filtering material filling said container and disposed contiguous to and inwardly of said capillary means, a plurality of filter material separator devices respectively embedded at different points within the mass of said filtering material to provide relatively unobstructed by-passes from one portion to another of said mass, and said container having at its central top portion an oil outlet means connected in communication with the oil discharge means of said casing.
4. A device of the kind described as defined in claim 3, wherein said filtering material of the oil cleansing means is impregnated with a solvent adapted to dissolve accumulating gums, tars and the like carried in the oil under treatment.

JOHN G. MACCORMACK. 25
